UNITED STATES PATENT OFFICE

2,096,271

WALL GRILLE

Fred M. Young, Racine, Wis., assignor to Young
Radiator Company, Racine, Wis.

Application April 2, 1934, Serial No. 718,568

2 Claims. (Cl. 98—114)

It is the intention, that the present patent shall cover by suitable claims, features of patentable novelty other than claimed in my pending application dated March 12, 1934, Serial No. 715,190.

5 The objects of my invention are: first, to deliver the air from the grille, fanlike; second, to evenly spread the passage of air throughout the grille assembly; third, to reduce surface friction to a minimum; fourth, to prevent whistling or air 10 interference noises; fifth, to provide a unit grille core assembly which may be easily fitted into any desired type of frame or housing; sixth, to provide a grille which is strong, light, inexpensive and pleasing in appearance; seventh, to provide a 15 grille core assembly without the use of bolts or complicated spacing members; eighth, to provide a grille core which, when assembled in a holding jig, a convenient means is provided for bonding the assembly together; ninth, to provide a grille 20 which may be assembled into any length and adapted to any degree of air spread without changing the parts from which the grill is made; tenth, to provide novel indentations across the fin surface properly spaced to thereby give the 25 assembly face a pleasing appearance, without in any way restricting the air passage; eleventh, to provide fin grooves at a transverse angle to thereby divert the air current upwardly or downwardly.

A further object of my invention is to provide 30 a suitable housing for a grille of the class, whereby the assembly is made without the use of bolts or screws, is simple, light and pleasing in appearance, having when desired, detachable means for holding the grille assembly into the frame assembly.

I accomplish these objects by means of novel 35 fin strips and novel spacer bars having means whereby the fins may be positioned at any desired transverse angle to the bars and variously spaced 40 apart thereon, and further by making the grille and holding frame in separate and independent units and providing means whereby the grille may be removably or permanently placed in the rearwardly extending opening of the housing.

45 To these and other useful ends my invention consists of matter hereinafter set forth and claimed and shown in the accompanying drawings in which:

Figure 1 is a front elevation of one form of 50 my grille and holding frame or housing.

Figure 2 is a horizontal section taken on line 2—2, of Figure 1.

Figure 3 is a top view of a grille unit as shown in Figure 2, except that the fin strips are variously 55 spaced and angled.

Figure 4 is an end section taken on line 4—4, of Figure 1.

Figure 5 is a fractional front view of a modified form of grille fin.

Figure 6 is a view similar to Figure 5, except 5 additional alternately positioned indentations in the fins are shown.

Figure 7 is a front view of a fin strip having a 10 full corrugated shape and showing a fraction of the spacer bars.

Figure 8 is a side view of a fin strip as shown 15 in Figures 1, 2, 3, and 4, except that the fin strip is indented as in Figure 5, the indentations, however, being positioned between the spacer bars and at an angle to the direction of air flow.

Figure 9 is a side view of a modified form of fin strip.

Figure 10 is a top view of a spacer bar as used 20 in connection with the fin strip shown in Figure 9.

Figure 11 is an enlarged fractional section as 25 shown in Figure 4, illustrating a modified form of side plate holding means.

Figure 12 is a modification of the end grille holding means as shown in Figure 2.

Figure 13 is a further modification of the end 25 grille holding means.

As thus illustrated in Figures 1, 2, 3 and 4, the grille or core assembly comprises a multiplicity of fin strips 10, and a number of spacer bars 11. The strips 10 are provided with spaced apart slits 30 12, which are adapted to snugly engage the bars 11, the fins being positioned at right angles to the bars, as indicated in Figures 1 and 2, and closely spaced thereon and bonded thereto, an assembling jig being provided wherein the fins project 35 therefrom, at least to the depth of the slits 12. A clamp is provided which hooks over the ends of bars 11, somewhat similar to that shown in Figure 2. This clamp is preferably made of a dissimilar metal from the bonding material and to which the 40 bonding material will not adhere. The projecting portion of the grille is then dipped into molten bonding material. Thus the fins 10 will be bonded to the bars 11 and a compact grille unit 45 provided.

I provide a grille housing comprising the front 50 frame 15, having a suitably sized opening for the grille as indicated in Figure 1. I provide end brackets 16, having feet 17 and inwardly projecting lips 18. Thus when the grille is placed into position on the rear of frame 15 the brackets 16 are made fast to the frame, preferably by spot welding members 17 and 15 together. Thus as 55 illustrated the grille will be held into position 55

through the brackets 16 and the lips 18 which rest on the ends of the bars 11.

I provide side brackets 19 (see Figure 4) which are similarly shaped to brackets 16 and having, preferably, inwardly projecting lips 20, which engage the fin strips as illustrated. Thus when the end and side members 16 and 19 are made fast to the frame 15, the grille and housing will comprise a compact, light and strong unit suitable for wall installations and the like.

In certain wall installations it is desirable to discharge the air fanlike. I accomplish this in the following manner (see Figure 3). The center fin strip 10^a is positioned on bars 11 at right angles thereto and each succeeding fin toward the ends is spaced slightly further apart than the preceding fin and each fin is also slightly angled greater than the preceding fin. Thus the fins diverge at an ever increasing angle and are spaced apart 20 at their rear edges at a gradually increasing distance from the center as clearly indicated, however it will be understood that all of the fins 10, may be angled in the same direction, or differently directioned in individual groups.

When air travels through a tube or duct, because of surface friction, it will travel faster at the center than at the outside. With an ordinary grille a much greater volume will be discharged at the center. I provide gradually increased spaces 30 between fins from the center toward the ends to counteract this tendency which is quite pronounced when the end fins are at an angle as shown in Figure 3. My gradually increased spacing and diverging angles tend to discharge the air fanlike at a uniform speed or volume and further, applicant's fins are thin and his spacer bars are narrow and since very few bars are needed there is very little resistance to the air stream. The air is discharged in evenly volumed 40 strata and thus the grille will operate efficiently and noiselessly.

In Figures 9 and 10, I illustrate a slightly different manner of fastening between the fin plates and spacer bars. In these figures the fin is designated by numeral 25, having slots 26, which are somewhat less in depth than slits 12. The bar 27 is provided with narrow slits 28, one for each fin. Thus slots 26 embrace the bars 27 and slits 28 embrace the strips 25, whereby when the assembly is completed the parts are bonded together and will then have the same appearance as the grilles shown in Figures 1, 2 and 4.

The appearance of a large number of spaced apart straight fin edges is not altogether pleasing. For the purpose of improving the appearance of my grille I preferably provide spaced apart indentations across the fin surface. The grooves thus formed are preferably positioned in transverse alignment as indicated in Figures 5 and 6, so as not to disturb the air flow. In Figure 5, the fin strip is designated by numeral 30 and the groove or indentations by numeral 31. These grooves are pressed into the fin and the projection thus formed on the opposite side of the fin is in alignment with the groove in the adjacent fin. In this design these grooves are also preferably in alignment with the bars 11.

In Figure 6, indentations 32 are spaced midway between the bars 11 and alternately positioned to the grooves 31. Thus when my improved grille is viewed from the front and at various angles the grooves or indentations tend to camouflage and present a more pleasing appearance.

In Figure 7, I illustrate a fin 35 which is corrugated. Thus it will be seen that variously po-

sitioned indentations may be used, and while I show curved indentations, they may be V shaped or the entire fin zigzagged in various shapes.

I have described and shown how the air current may be discharged fanlike. In Figure 8, 5 I illustrate a fin 40 having indentations 41, similar to those shown in Figures 5 and 6, except that they are at an angle transversely; thus the fins may be positioned so as to divert the air upward or downward, or any combination of angles may be used for a desired purpose; for example, the indentations 41 may be alternately directed on alternate fins, thus to cause the air to be discharged fanlike vertically.

In Figures 11, 12, and 13, I illustrate modifications. Figure 11 is very similar to the assemblies shown in Figures 2 and 4, differing only in the side plates. The side bracket 45 extends rearwardly as indicated and a supplemental bracket 46 is provided having inwardly projecting lips 47. 20 Thus the assembly is similar to that shown in Figure 4, except that 45 terminates on a plane with the rear end of 16, thus forming a slightly more desirable means for connection to the air duct tube. In Figure 13, I illustrate an end 25 bracket 48, having a supplementary bracket 49 similar to the side bracket shown in Figure 11.

In all of the figures thus far described I contemplate spot welding the frame to the side and end plates and in Figures 11 and 13, I contemplate spot welding members 46 and 49 to their brackets 45 and 48. Thus the grille is not easily removed. It may be desirable to detachably hold the grille to the housing. This may be accomplished by attaching members 46 and 49 by means 35 of bolts.

Figure 12 illustrates a still further modification wherein the end bracket 50 is preferably spot welded to the frame and side plates 51 are not provided with inwardly projecting lips. An L shaped holding member 52, is adapted to engage the bars 11, as indicated, and be held to the end plates 50 by means of bolts 53. Thus there is provided a rearwardly extending enclosure for the grille suitable for convenient connection to the air duct and the grille is removably held against the frame 15 by means of bracket 52.

By referring to Figure 3, it will be observed that the front face formed by the fins will present a slightly convex shape on its outlet side transversely. Thus the grille will be slightly bent at its ends toward the frame when the bracket 52 is made fast to the end plates. It may therefore be stated that the grille will be under spring tension, to thereby hold it from rattling or working loose. 55

Thus I have provided a simple and light frame and simple and light end and side plates forming a suitable housing for my improved grille core, suitable means for connection to the air duct, and either permanent or detachable means for 60 holding the grille in the housing.

Having thus shown and described my invention, I claim:

1. A wall grille of the class described, comprising a number of spacer bars having a multiplicity of closely spaced fin strips mounted transversely thereon forming a grille, a housing comprising a front frame having rearwardly extending side and end members forming an enclosing outer frame for said grille, means whereby the front of said grille is curved rearwardly toward the ends of and in a plane parallel to said spacer bars, means on said end members contacting said spacer bars whereby said bars are curved forwardly and said grille is yieldingly held against said frame. 70

2. A grille of the class, comprising a number of spacing bars, a multiplicity of strip fins each having a number of spaced apart slits cut transversely in their rear edges, said fins assembled transversely on said bars in spaced apart relation the slits closely embracing said bars and

bonded thereto to thereby form a unitary grille, said fins having a number of spaced apart grooves pressed into their sides for their entire width at an angle to the direction of air flow.

FRED M. YOUNG. 5
